UNITED STATES PATENT OFFICE.

JOHN W. MILLER, OF AKRON, OHIO.

WELL-DRILLING MACHINE.

No. 816,988.

Specification of Letters Patent.

Patented April 3, 1906.

Application filed May 23, 1905. Serial No. 261,781.

To all whom it may concern:

Be it known that I, JOHN W. MILLER, a citizen of the United States, residing at Akron, in the county of Summit and State of Ohio, have 5 invented new and useful Improvements in Well-Drilling Machines, of which the following is a specification.

This invention relates to portable machines for drilling oil, gas, and other deep wells.

10 The object of this invention is to provide improved mechanism for actuating a drilling-cable in the operation of spudding and to make said mechanism adaptable for beam-drilling, as desired.

15 The invention further contemplates providing an improved means for actuating the drilling-cable so as to accelerate its downward or working stroke and make its ascent therefrom relatively slow or gradual.

20 With the foregoing and other objects in view the invention consists in the novel construction, combination, and arrangement of parts constituting the invention, to be hereinafter referred to, and illustrated in the accompanying drawings, which form a part of this specification, in which is shown the preferred embodiment of the invention; but it is to be understood that changes, variations, and modifications can be resorted to which 30 come within the scope of the claims hereunto appended.

In the drawings, in which similar reference-numerals indicate like parts in the different figures, Figure 1 is a perspective view of so 35 much of a well-drilling machine as will illustrate the adaptability of this invention thereto. Fig. 2 is a plan view of the rear portion of the frame and mechanism shown in Fig. 1, and Fig. 3 is a section of Fig. 2 at the line X.

40 In the drawings the reference-numerals 1 1 indicate the two side beams constituting a portion of the horizontal frame of the machine. This frame is suitably mounted upon ground-wheels 2 2, by which the machine 45 is transported. Mounted between and supported by the rear end of the beams which constitute the frame is an ordinary steam-boiler 3 of any preferred type suitable for this style of machine. On one of the beams 50 1 is mounted a samson-post 4, on the upper end of which is pivotally mounted a walking-beam 45 and having attached to its left end a pitman 5. On the front ends of the beams 1 1 is mounted a mast or derrick 6, braced 55 from the rear by bars 7. Extending between the beams and usually located on either side

of the place where the samson-post is located are two cross-bars 8 8, and mounted on these bars 8 8 is an ordinary upright engine 9, adapted to revolve a horizontal shaft 10, 60 having a large balance-wheel 42 at one end and a pulley 11 at the opposite end.

Mounted in bearings 12 12 on the beams 1 1 immediately in front of the boiler 3 is a transverse shaft 13, having on one end a 65 large pulley 14, over which is passed a belt 15, which also passes over the pulley 11 on the engine-shaft 10. Power is communicated to the shaft 13 by means of the belt 15 actuating the pulley 14. The front end of 70 the shaft 13 bears a crank-arm 16, provided with a wrist-pin 17, having mounted thereon shoes 18.

Mounted on the beams 1 1 and in front of the shaft 13 are a pair of bearings 21, in which 75 is mounted for rotation a shaft 20. This shaft bears at one end a two-part crank-arm, consisting of a rigid member 19, fixedly secured to the shaft and having cut in its extended portion a groove 19^a. Attached by 80 means of cap-screws 19^b to the arm 19 is a strap 19^c, which constitutes the other part of said crank-arm, and this strap converts the groove 19^a into an elongated slot, which is adapted and arranged to receive the wrist- 85 pin 17 and its shoes 18.

Rigidly secured on the shaft 20 is an oscillating arm 22, bearing at its upper end a spudding-sheave 23, arranged to engage and operate the drilling-cable. 90

Mounted in bearings 24 on the beams 1 1 is a shaft 25, bearing on its nearer side a large spur-gear 26, and in its central portions between the beams 1 1 a reel 27. Meshing into the spur-gear 26 is a shrouded pinion 28, 95 mounted on a shaft 29, supported in bearings 49, mounted on the beams 1 1. The shaft 29 where it passes through its bearing on the farther beam 1 is inclosed by an eccentric sleeve 30, to which is attached on the 100 farther side of the bearing an arm 31, and to the upper end of this arm 31 is attached a rod 32, having a handle 33, by which it is operated. Beyond the arm 31 the shaft 29 bears a friction-pulley 34 of such a diameter 105 that when the arm 31 is thrown in one direction the eccentric sleeve 30, in which is mounted the shaft 29, will force the face of the pulley 34 against the outer face of the belt-pulley 14 and cause frictional engagement between these two.

Mounted on a housing, extending between

the cross-bars 8, is an idler-sheave 36, over which the drilling-cable is passed in its course from the reel 27 to the oscillating sheave 23, and from there it passes upward over a 5 sheave in the top of the mast or derrick and from thence downward into the well in the ordinary manner.

A reel 37 is placed on a shaft 47, mounted in bearings 48 on the beams 11, and around 10 this reel is passed a sand-pump cable 38. The shaft 47, on which the reel 37 is mounted, is provided with an eccentric sleeve 46 in its bearing, which sustains it on the farther beam 1 in precisely the same manner as the 15 shaft 29 is surrounded by the eccentric sleeve 30, and a rocking arm 39 is attached to this eccentric sleeve. This eccentric sleeve and the bearing in which it is revolved is hidden by the side of the reel in Fig. 1; but as its operation 20 is exactly the same as the eccentric sleeve for the shaft 29 it is believed that a further description of it is unnecessary. This shaft 47, which bears the reel 37, has a pulley 40, which is arranged to engage the inner 25 face of the pulley 14 to one side of the spokes thereof in the same manner that the pulley 34 engages the outer face of the pulley 14. The operating-arm 39 is provided with a connecting-rod 41, having a handle at a 30 convenient place to be operated by the engine attendant.

The operation of this device is as follows: In ordinary beam - drilling the two - part 35 crank-arm is disengaged from connection with the wrist-pin 17 by removing the cap-screws 19^b and separating the member 19^c from the arm 19 and removing the wrist-pin 17 and its shoes 18 from the crank-arm 16. A wrist-pin is then inserted in one of the 40 openings 50 shown to exist in the crank-arm 16 and the end of the pitman 5 fitted over this pin and ordinary beam-drilling may be practiced as long as desired.

In using this device for spudding the parts 45 will be in the position indicated in the drawings and the drilling-cable will pass from the pulley on the top of the mast or derrick down around the spudding - sheave 23 and from thence around the idler-sheave 36 to the reel 50 27. The revolution of the large pulley 14, driven by the belt 15 from the engine-pulley 11, will reciprocate the wrist-pin 17 and its shoes 18 in the slot 19^a formed in the arm 19, causing an oscillating motion to be imparted 55 to the arm 22 on the shaft 20. This arrangement just described is such that a quick downward movement or stroke is imparted to the arm 19, and as this movement allows the loosening or slackening of the working 60 cable it imparts a quick downward stroke to the tool suspended on this cable, which is a very desirable effect to be produced in well-drilling machines of this character, and as the crank-arm 16 continues its revolution the 65 effect will be to cause a relatively slow move-

ment of the oscillating sheave when raising the tools for the next stroke. When it is desired to raise tools from the well, the handle 33 is drawn forward, swinging the bar 32 and the arm 31 on the eccentric sleeve 30, 70 which throws the face of the pulley 34 into frictional engagement with the face of the pulley 14, causing a rotation of the pinion 28, which on account of its meshing into the large spur-gear 26, revolves the reel 27, winding up the working cable, and thus raises the tools from the well.

It will be further noted that the shaft 13, on which is the crank-arm 16, the shaft 20, on which is the rocking arm 19, the main reel-shaft 25, on which is the spur-gear 26, and the pinion-shaft 29, bearing the pinion 28, are all mounted conveniently above the side beams 11, so that none of the mechanism used in the operation of drilling is placed below the 80 frame of the machine. This arrangement of the operative parts of the machine is one of great importance in this species of machine for this reason, that, as has been before stated, the machines are portable and are 85 transported over roads at all seasons of the year, some of which are so muddy that the machine will frequently sink therein to the under sides of the beams 11, and if the operative mechanism is placed below these beams 90 11 there is great liability of breaking or injuring the same when passing over even ordinarily fair roads. It will be further noted that the arrangement of the parts in this device are of unusual simplicity and as the 95 mechanism of well-drilling machines is handled in the field distant from repair-shops simplicity, ease of manipulation, and repair become of prime importance to the user of this class of devices, and, further, the extreme 100 simplicity of the device gives to the manufacturer thereof the opportunity to make the working parts which are subjected to great strain or unusual weight of greater 105 strength to resist the possibility of accidental 110 breaking.

What I claim, and desire to secure by Letters Patent, is—

1. A device of the class described, comprising a portable frame, a boiler carried 115 thereby, an engine carried by the frame, connections between the boiler and the engine, a transversely-extending shaft mounted above the top edge of said frame, a pulley mounted on one end of said shaft, a belt connection between 120 said pulley and said engine, a crank-arm secured to the opposite end of said shaft and provided with a plurality of perforations, a transversely-extending second shaft mounted above the top edge of said frame at one 125 side of said first-mentioned shaft, a two-part crank-arm the parts of which are separable from each other fixedly secured to one end of said second shaft and provided with an elongated slot, a wrist-pin detachably mounted 130

in any one of said perforations and extending through said slot, a pair of shoes carried by the free end of the wrist-pin and engaging the longitudinal walls of said slot for operating said separable crank-arm when the perforated crank-arm is operated, said perforations in said crank-arm permitting of the adjusting of the wrist-pin to vary the stroke imparted to the separable crank-arm, a single and upwardly-extending oscillatory arm fixedly secured on said second shaft intermediate the sides of said frame, an open spudding cable-receiving sheave mounted on one side of said oscillatory arm, movable in unison therewith and adapted to permit of the detaching of the cable without removing the said oscillatory arm, a cable-reel mounted on said second shaft intermediate the sides of said frame, an open spudding cable-receiving sheave mounted on one side of said oscillatory arm, movable in unison therewith and adapted to permit of the detaching of the cable without removing the said oscillatory arm, a cable-reel mounted for rotation above the top edge of said frame, a derrick at one end of said frame, a cable on said reel extending therefrom to and partially around said cable-receiving sheave to the top of the derrick and adapted to be actuated by the oscillations of said cable-receiving sheave, and a supporting means mounted upon the top edge of said frame for said shafts and reel, substantially as described.

2. A device of the class described, comprising a portable frame, a boiler carried thereby, an engine carried by the frame, connections between the boiler and the engine, a transversely-extending shaft mounted above the top edge of said frame, a pulley mounted on one end of said shaft, a belt connection between said pulley and said engine, a crank-arm secured to the opposite end of said shaft and provided with a plurality of perforations, a transversely-extending second shaft mounted above the top edge of said frame at one side of said first-mentioned shaft, a two-part crank-arm the parts of which are separable from each other fixedly secured to one end of said second shaft and provided with an elongated slot, a wrist-pin detachably mounted in any one of said perforations and extending through said slot, a pair of shoes carried by the free end of the wrist-pin and engaging the longitudinal walls of said slot for operating said separable crank-arm when the perforated crank-arm is operated, said perforations in said crank-arm permitting of the ad-

justing of the wrist-pin to vary the stroke imparted to the separable crank-arm, a single and upwardly-extending oscillatory arm fixedly secured on said second shaft intermediate the sides of said frame, an open spudding cable-receiving sheave mounted on one side of said oscillatory arm, movable in unison therewith and adapted to permit of the detaching of the cable without removing the said oscillatory arm, a cable-reel mounted for rotation above the top edge of said frame, a derrick at one end of said frame, a third shaft extending transversely of and above said frame, a sand-line reel mounted on said third shaft, a pulley mounted on the end of said third shaft and arranged in operative relation with respect to the pulley on said first-mentioned shaft, means for throwing said pulley on said sand-line-reel shaft into frictional engagement with the inner face of the pulley on said first-mentioned shaft, a fourth shaft extending transversely of and above said frame, said cable-reel mounted on said fourth shaft, a spur-gear mounted on said fourth shaft and arranged exteriorly of one side of said frame, a pinion adapted to engage said spur-gear, a fifth shaft extending transversely of and above said frame for supporting said pinion, a pulley mounted on said fifth shaft and arranged in operative relation with respect to the periphery of the pulley on the first-mentioned shaft, means for throwing the said pulley on the fifth shaft into operative engagement with the periphery of the pulley on said first-mentioned shaft, a cable arranged on said reel carried by the fourth shaft and extending therefrom to and partially around said sheave to the top of said derrick, whereby said cable is actuated by the oscillations of said sheave, and means mounted upon the top edge of said frame for supporting all of said shafts, substantially as described.

In testimony whereof I have hereunto set my hand in presence of two subscribing witnesses.

JOHN W. MILLER.
